The ornamental design for an automobile front grille, as shown and described.

DESCRIPTION

FIG. 1 is a front and right side perspective view of an automobile front grille showing my new design;

FIG. 2 is a rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a front elevation view thereof in which a single LED bar is illuminated across the front inner surface;

FIG. 9 is a front elevation view thereof in which two rows of LED bars are illuminated across the front inner surface;

FIG. 10 is a front elevation view thereof in which three rows of LED bars are illuminated across the front inner surface;

FIG. 11 is a front elevation view thereof in which four rows of LED bars are illuminated across the front inner surface; and,

FIG. 12 is a front elevation view thereof in which five rows of LED bars are illuminated across the front inner surface.

FIGS. 1-7 show the automobile front grille in which the LED bars are not illuminated. In contrast, FIGS. 8-12 show the LED bars during their five modes of illumination.
